PROCESS FOR THE PRODUCTION OF
LUBRICATING OILRobert E. Haylett, Long Beach, Calif., assignor to
Union Oil Company of California, Los Angeles,
Calif., a corporation of CaliforniaNo Drawing. Application October 22, 1932,
Serial No. 639,154

8 Claims. (Cl. 196—13)

This invention relates to a process for the production of lubricating oil. More specifically, it relates to a process for the production of lubricating oil from petroleum by the use of solvents.

5 The lubricating oil components of many crude oils are highly complex in character and consist of a mixture of hydrocarbons having widely different characteristics. Those hydrocarbons present which exhibit a minimum change in viscosity with 10 a change in temperature, i. e., have a low viscosity temperature susceptibility are considered to be most valuable as lubricants for internal combustion engines whereas those hydrocarbons present which exhibit the maximum change in viscosity 15 with a change in temperature, i. e., have a high viscosity temperature susceptibility, are considered to be the least valuable. Lubricants which exhibit a low temperature viscosity susceptibility are often referred to as the paraffinic oils whereas those 20 which exhibit a high temperature viscosity are referred to as non-paraffinic oils.

At the present time the method most commonly used for separating the lubricating oil fractions of petroleum into paraffinic and non-paraffinic oils 25 consists in treating these fractions with liquid sulphur dioxide. For example, a lubricating oil distillate containing paraffinic and non-paraffinic oil is extracted at a temperature ranging from about 0° F. to —10° F. with liquid sulphur dioxide. The 30 liquid sulphur dioxide dissolves the non-paraffinic fractions present in the oil and due to the relatively high specific gravity of the sulphur dioxide solution of non-paraffinic oil as compared to the liquid sulphur dioxide insoluble oil present in the 35 distillate it is possible to obtain a separation, a gravity separation, of the paraffinic oil from the non-paraffinic fractions dissolved in liquid sulphur dioxide. Upon settlement the paraffinic oil obtained, referred to as the "raffinate", forms an upper layer which may be decanted away and distilled for the removal of any remaining sulphur dioxide present after which the oil may be further treated with acid, alkali and clay to produce a 40 finished lubricant. The lower layer formed after 45 settlements contains the major portion of the non-paraffinic oil dissolved in liquid sulphur dioxide. This solution may be withdrawn from the extraction vessel and distilled to recover the sulphur dioxide and the non-paraffinic oil which is often 50 referred to as "extract".

Extracts produced from petroleum hydrocarbon mixtures by the use of liquid sulphur dioxide at relatively low temperatures are usually highly non-paraffinic in character. Complete separation 55 of the non-paraffinic fractions from the raffinate

oil cannot be obtained because the liquid sulphur dioxide apparently exhibits a tendency to leave a certain amount of the non-paraffinic components in the raffinate phase. This is especially true where the extraction has been carried out at temperatures between —10° F. and —20° F. At these temperatures the solvent power of the liquid sulphur dioxide towards the oils present which are semi-non-paraffinic is materially lessened. Consequently, these components are forced into raffinate phase and as a result the temperature viscosity susceptibility of this oil is increased. By proper selection of temperature this same effect may be produced by most solvents which exhibit any appreciable solvent power for the non-paraffinic fractions in a hydrocarbon mixture. Thus by proper selection of temperature solvents such as aniline, nitrobenzene, furfural or selenium oxychloride will separate a highly non-paraffinic extract and a raffinate which is more or less contaminated with non-paraffinic fractions.

Dichlorethyl ether (B' B') is another solvent which is used to separate hydrocarbon oils into paraffinic and non-paraffinic fractions. The usual method of employing this solvent is to mix it 25 with the oil to be treated, heat the oil to a temperature sufficiently high to obtain complete miscibility between the oil and the ether, cool the solution to a temperature somewhat below the point of complete miscibility and separate the oil which 30 is insoluble at this somewhat lowered temperature from the dichlorethyl ether and dissolved oil. Due to the relatively greater specific gravity of the oil dissolved in the ether over the undissolved oil portion 35 the ether solution of oil forms a lower layer or phase in the extraction vessel and the ether insoluble oil forms a lower layer or phase. These layers may then be separated by simple decantation methods and then distilled to separate the oils from their dichlorethyl ether contents. The 40 temperature at which the oil to be extracted becomes completely miscible with the dichlorethyl ether, of course, will vary but generally this temperature is within the range of 100° F. to 175° F. After complete miscibility of the ether and the oil 45 the temperature of the oil-ether solution is lowered at least 40° F. where the paraffinic oil separates from the non-paraffinic oil dissolved in the ether. The paraffinic oil forms the upper layer and the non-paraffinic oil dissolved in the dichlorethyl 50 ether forms the lower layer. These layers are separated, as has been described, by simple decantation and then distilled to separate the dichlorethyl ether from the oils.

Raffinates produced from hydrocarbon mix- 55

tures by the use of B B' dichlorethyl ether at relatively high temperatures are highly paraffinic in nature but the extracts so produced usually contain appreciable amounts of oil which have 5 temperature viscosity susceptibility characteristics intermediate between the most paraffinic oils and the least paraffinic oils. Thus it appears that while dichlorethyl ether is capable at relatively high temperatures of separating raffinates 10 from hydrocarbon mixtures which are highly paraffinic in character there is apt to be a considerable loss of a portion of the paraffinic fractions in the extract phase. Furthermore raffinates may be produced from hydrocarbon mixtures similar 15 to those separated by B B' dichlorethyl ether at relatively high temperatures by extracting the hydrocarbon mixture with selective solvents such as aniline, nitrobenzene, furfural, methyl cellosolve, cellulose acetate, cresylic acid, phenol or 20 phenyl acetate near the critical solution temperature of the oil and the solvent. At this temperature only the most paraffinic fractions present in the hydrocarbon mixture remain undissolved.

It therefore appears to be highly desirable to 25 extract hydrocarbon mixtures containing paraffinic and non-paraffinic hydrocarbons with a solvent capable of forming a highly non-paraffinic fraction and then re-extracting the raffinate so produced with a solvent capable of producing a 30 highly paraffinic fraction. By extracting the hydrocarbon mixture with a solvent capable of removing the highly non-paraffinic fractions those components are removed from the hydrocarbon mixture which lessen the effectiveness of 35 the solvent employed to separate the highly paraffinic fractions. Thus, if the oil is first extracted with a solvent of the liquid sulphur dioxide type and then the raffinate so produced is re-extracted with a solvent of the B B' dichlorethyl ether 40 type, a second raffinate is produced which is highly paraffinic in character. The liquid sulphur dioxide removes from the oil at relatively low temperatures those fractions which are highly non-paraffinic in character and which tend to 45 lessen the effectiveness of the dichlorethyl ether to separate a highly paraffinic raffinate from the oil remaining undissolved from the sulphur dioxide extraction.

It is, therefore, an object of my invention to 50 extract hydrocarbon mixtures into paraffinic and non-paraffinic fractions by means of a plurality of solvents.

It is another object of my invention to extract 55 hydrocarbon mixtures with a solvent capable of forming a highly non-paraffinic fraction and a paraffinic fraction and thereafter to re-extract the paraffinic fraction so produced with another solvent capable of separating therefrom a highly paraffinic fraction.

60 It is a further object of my invention to separate hydrocarbon mixtures with liquid sulphur dioxide into a raffinate and an extract and thereafter re-extract the raffinate with B B' dichlorethyl ether.

65 It is still another object of my invention to separate hydrocarbon mixtures into an extract and a raffinate with a solvent at one temperature and then re-extract the raffinate with another solvent at a different temperature.

70 My process is applicable to lubricating oil distillates, petroleum residues or hydrocarbon mixtures containing lubricating oil hydrocarbons. Providing a hydrocarbon mixture containing asphalt is employed as raw stock to be treated I 75 may first extract such residue with a solvent ca-

pable of dissolving the oil but which leaves the asphalt remaining after the extraction as an undissolved residue. The solvent may then be distilled away from the oil after which the oil may be separated into its paraffinic and non-paraffinic fractions by the process which I have previously described. Solvents which I may employ to separate the asphalt from the oil are naphtha, gasoline and liquefied normally gaseous hydrocarbons, such as ethane, propane, butane or pentane or mixtures thereof. The liquefied normally gaseous hydrocarbons which I may employ are liquids at ordinary temperature if maintained under pressure. In separating the asphalt from the oil with these hydrocarbons I commingle the asphaltic oil with the liquefied normally gaseous hydrocarbon at a temperature of 50-75° F. and under sufficient pressure to maintain the light liquid hydrocarbon solvent in the liquid state. Usually three volumes of the light liquid hydrocarbon solvent to one part of the asphaltic oil will cause satisfactory separation of the asphalt, however, I may use a greater or less proportion of solvent. After separation of the solvent solution of oil from the undissolved asphalt the solvent is distilled away from the oil and the latter is then separated into its paraffinic and non-paraffinic components by such solvents as liquid sulphur dioxide and B B' dichlorethyl ether.

As an example of the preferred method of carrying out my process, a lubricating oil fraction derived from a Mid-Continent or Western crude oil is commingled under pressure and at a temperature of approximately -15° F. with liquid sulphur dioxide, the commingled mass is then allowed to settle until there is formed an upper layer containing the paraffinic oil and a lower layer containing the highly non-paraffinic oil. These fractions are distilled to remove their content of sulphur dioxide after which the paraffinic fraction is mixed with B B' dichlorethyl ether in the proportion of three parts of the ether to one part of oil. This mixture is heated to a temperature sufficiently high to obtain complete miscibility between the oil and ether after which the solution is cooled to a temperature approximately 40° F. below the point of complete miscibility. At this temperature there separates from solution an oil which is very highly paraffinic in character. This highly paraffinic fraction has a lower specific gravity than the non-paraffinic oil dissolved in the dichlorethyl ether. Upon settling the highly paraffinic oil forms an upper layer and the dichlorethyl ether solution of non-paraffinic oil forms a lower layer. These layers are separated by simple decantation. The dichlorethyl ether is then separated from the highly paraffinic oil and the non-paraffinic oil by distillation. The highly paraffinic fraction may then be further treated, if desired, with acid, alkali and/or clay to obtain any further refining necessary to produce a finished oil. Usually when acid treatment is employed subsequent to extraction with dichlorethyl ether I find that the oil is sufficiently purified by treatment with 5-10 pounds of 93% sulphuric acid per barrel of oil.

The temperatures which I may employ during extraction depends upon the type of products desired. When the initial extraction is carried out with a solvent such as liquid sulphur dioxide 70 the temperature employed governs, to a great extent, the characteristics of the extract and raffinate so produced. In general the lower the temperature employed during extraction the more non-paraffinic will be the extract produced and 75

the more contaminated will be the raffinate with non-paraffinic constituents. As the effectiveness of the B B' dichlorethyl ether to separate a highly paraffinic fraction from the sulphur dioxide 5 raffinate depends somewhat upon the degree of contamination of the sulphur dioxide raffinate with non-paraffinic fractions, it is important that the temperature selected for the initial extraction with liquid sulphur dioxide be within the 10 range wherein the raffinate will contain a minimum amount of the non-paraffinic fractions. Furthermore the temperature which I may employ during the extraction of the sulphur dioxide raffinate with B B' dichlorethyl ether will govern to some extent the degree of paraffinicinity of the raffinate fraction. As the temperature employed for extraction of the sulphur dioxide raffinate with B B' dichlorethyl ether approaches the point of complete miscibility a raffinate is 20 produced which exhibits a maximum degree of paraffinicinity but the yield of raffinate is correspondingly low as only the most paraffinic fractions will remain insoluble in the dichlorethyl ether at this temperature.

25 Thus extraction of the hydrocarbon mixture at a low temperature with sulphur dioxide produces an extract which is highly non-paraffinic and a raffinate which is more or less contaminated with non-paraffinic oil fractions. If the 30 raffinate fraction produced by extracting the hydrocarbon mixture at low temperature with sulphur dioxide is re-extracted at a relatively high temperature with B B' dichlorethyl ether, i. e., within a few degrees of the temperature of complete miscibility, it is possible to obtain an oil fraction insoluble in the B B' dichlorethyl ether which is highly paraffinic in character.

As a modification of my process I may first extract the hydrocarbon mixture with a solvent 40 of the B B' dichlorethyl ether type and then re-extract the extract so produced with a solvent of the sulphur dioxide type. The B B' dichlorethyl ether is capable of producing a raffinate fraction which is relatively free from non-paraffinic constituents but the extracts produced by extraction with B B' dichlorethyl ether are usually contaminated with paraffinic oil fractions. This is especially true where the temperatures during extraction have been maintained at a relatively high temperature. High temperature extraction with B B' dichlorethyl ether tends to force paraffinic fractions into the extract phase. By extracting a hydrocarbon mixture containing paraffinic and non-paraffinic fractions at a relatively high temperature with B B' dichlorethyl ether a highly paraffinic raffinate can be produced and then by re-extracting the extract from the B B' dichlorethyl ether extraction with liquid sulphur dioxide at a relatively low temperature, 50 an extract can be obtained which is highly non-paraffinic in character. At the same time the extraction of the B B' dichlorethyl ether extract at the low temperature with liquid sulphur dioxide produces a raffinate fraction which has characteristics intermediate between paraffinic and non-paraffinic oils. This fraction is useful as a second grade lubricant and can be employed for purposes where the temperature viscosity susceptibility of the oil is not an essential characteristic.

55 In general the temperatures employed during extraction with B B' dichlorethyl ether are within 40° F. of the temperature of complete miscibility and the temperatures employed in extraction with liquid sulphur dioxide are at least

—15° F. or lower. I do not propose to bind myself within these limits, however, as it may be desirable in many cases to carry out the extraction with B B' dichlorethyl ether at a temperature of more than 40° F. below the point of complete miscibility and to extract with liquid sulphur dioxide at temperatures above —15° F.

5 The foregoing example is merely descriptive of one method of carrying out my process and is not to be taken as limiting the invention which I claim.

I claim:

1. A process for the production of lubricating oil from a hydrocarbon oil mixture which comprises extracting said oil with a solvent of the liquid sulphur dioxide type into a raffinate and an extract and subsequently extracting said raffinate into a plurality of fractions with a solvent of the B B' dichlorethyl ether type.

2. A process for the production of lubricating oil from a hydrocarbon oil mixture which comprises extracting said oil with a solvent of the B B' dichlorethyl ether type into a raffinate and an extract and subsequently extracting said extract into fractions with a solvent of the liquid sulphur dioxide type.

3. A process for the production of lubricating oil from a hydrocarbon oil mixture which comprises extracting said oil with a solvent of the sulphur dioxide type into a raffinate fraction and fractions dissolved in said solvent of the sulphur dioxide type, re-extracting said raffinate fraction with a solvent of the B B' dichlorethyl ether type into a second raffinate fraction and fractions dissolved in said solvent of the B B' dichlorethyl ether type and subsequently separating said solvents from said fractions.

4. A process for the production of lubricating oil from a hydrocarbon oil mixture which comprises extracting said oil at a relatively high temperature with a solvent of the B B' dichlorethyl ether type into a raffinate and an extract and subsequently extracting said extract into a plurality of fractions at a relatively low temperature with a solvent of the liquid sulphur dioxide type.

5. A process for the production of lubricating oil from a hydrocarbon oil mixture which comprises extracting said oil at a relatively low temperature with a solvent of the liquid sulphur dioxide type into a raffinate and an extract and subsequently extracting said raffinate into a plurality of fractions at a relatively high temperature with a solvent of the B B' dichlorethyl ether type.

6. A process for the production of lubricating oil from a hydrocarbon oil mixture which comprises extracting said oil with liquid sulphur dioxide into an extract and a raffinate and subsequently extracting said raffinate into a plurality of fractions with dichlorethyl ether.

7. A process for the production of lubricating oil from a hydrocarbon oil mixture which comprises extracting said oil at low temperatures with liquid sulphur dioxide into an extract and a raffinate and subsequently extracting said raffinate into a plurality of fractions with dichlorethyl ether.

8. A process for the production of lubricating oil from a hydrocarbon oil mixture which comprises extracting said oil at low temperatures with liquid sulphur dioxide into an extract and a raffinate and subsequently extracting said raffinate at high temperatures into a plurality of fractions with B B' dichlorethyl ether.
